CLAIM

The ornamental design for an unmanned aerial vehicle, as shown and described.

DESCRIPTION

FIG. 1 is a front perspective view from above an embodiment of an unmanned aerial vehicle;
FIG. 2 is a rear perspective view from above the unmanned aerial vehicle of FIG. 1;
FIG. 3 is a front view of the unmanned aerial vehicle of FIG. 1;
FIG. 4 is a left side view of the unmanned aerial vehicle of FIG. 1;
FIG. 5 is a right side view of the unmanned aerial vehicle of FIG. 1;
FIG. 6 is a rear view of the unmanned aerial vehicle of FIG. 1;
FIG. 7 is a top view of the unmanned aerial vehicle of FIG. 1; and,
FIG. 8 is a bottom view of the unmanned aerial vehicle of FIG. 1.
The broken lines depict portions of the unmanned aerial vehicle that form no part of the claimed design.

1 Claim, 8 Drawing Sheets
